UNITED STATES PATENT OFFICE.

EMIL SCHLOSS, OF NEW YORK, N. Y.

RIBBON.

Application filed January 6, 1926. Serial No. 79,697.

This invention relates to ribbons such as are particularly adapted for the tying of floral bouquets or designs although not restricted to such use. This application 5 forms a continuation in part of my copending application, Serial No. 758,330 filed December 27, 1924.

An important object of my invention is to provide in a ribbon structure an effective means for stiffening the same along its margins whereby the ribbon when tied into a bow may be rendered self-sustaining thus insuring, as far as possible, the original 15 neatness or neatness in appearance of the bow, the stiffening means being of a colorable material susceptible to dyeing in order to provide a harmonizing, contrasting or similar color as desired with respect to the color of the ribbon body. It is also preferable 20 that the stiffening means have sufficient resiliency to not only retain the ribbon in its original position but also to insure that the ribbon, when tied in a bow or the like, will return to its normal position when displaced therefrom.

Other objects and certain advantages of the invention will become apparent from the following description when taken in connection with the accompanying drawings in which—

Figure 1 is a fragmental face view of a ribbon structure embodying my invention.

Figure 2 is an enlarged fragmental detail view showing the arrangement of the 35 stiffening means employed in the structure shown in Figure 1.

Figure 3 is a still further enlarged sectional view taken transversely through the ribbon shown in Figure 2.

In the drawings wherein for the purpose of illustration is shown what I at present consider the preferred form of my invention, the numeral 5 indicates, as a whole, a ribbon of a gauze-like fabric particularly 45 adapted to be used in the tying of floral bouquets or other floral designs. As is well-known, this fabric is relatively flexible and lacking in resiliency. The warp threads entering into the body of the ribbon 50 are indicated by the numeral 6 whereas the woof threads are indicated by the numeral 7. The body of the ribbon structure herein shown is reinforced at opposite longitudinal edges by relatively coarse warp threads 6' and is also reinforced along its margins by 55 similar threads 6''. In order, however, to

additionally reinforce the ribbon structure along its margins I employ a plurality of strands 8 of preferably resilient cellulose material such as viscose, nitro-cellulose, 60 pyroxylin, or the like, running longitudinally of the ribbon in close proximity to the reinforcing warp threads 6'. These strands 8 are grouped together as shown most clearly in Figure 3 and may be considered as reinforcing warp threads supplemental to those indicated by the numeral 6'. In order to further reinforce the ribbon along its longitudinal margins I have provided a second group of strands 9, 70 identical with those indicated by the numeral 8, arranged in proximity to the reinforcing warp threads 6''. The threads 9, like those indicated by the numeral 8, are grouped together as shown most clearly in 75 Figure 3.

As will be noted the reinforcing warp threads 6' and 6'', being somewhat coarser than the material from which the ribbon body is formed, lend to the structure, as a 80 whole, a border effect which although desirable in certain instances may be dispensed with in other cases by substituting for the relatively coarse material, used for these threads, the same material as is used 85 for the warp threads 6.

The threads 8 and 9, respectively, being of a relatively stiff but also resilient material and also being of a somewhat enlarged cross sectional area with respect to the warp and woof threads 6 and 7, respectively, lend, as will be readily appreciated, sufficient 90 rigidity or reinforcement to the ribbon body to render it self-sustaining when tied into bow form, thus making it possible to preserve the original neatness with which the 95 bow was originally tied. The resiliency of the threads 8 and 9 is at the same time sufficient, so that, when the ribbon is arranged in any desired form as in a bow, it may be 100 displaced from its position but will always return thereto. That is, each thread may be bent laterally of its length but will return to its original position, when the bending force is removed. However, this resiliency 105 is not so great that it will preclude ready shaping of the ribbon into a desired form or design. The resilient threads may be shaped with the fabric but possess sufficient resiliency so that they will retain the 110 shape given to them against any ordinary treatment to which the fabric is likely to

be subjected. Furthermore, the reinforcing threads 8 and 9 when of a cellulose material may be readily dyed in any desired color before incorporating the same into the 5 ribbon structure in order to produce any desired color effect, in so far as these reinforcing threads are concerned, with respect to the ribbon in its entirety. On the other hand these threads may be dyed simultaneously with the dyeing of the ribbon after the structure has been completed, in which case the reinforcing threads will, of course, present the same color as that of the body of the ribbon. From what has just been 10 said, however, it does not follow that these reinforcing threads may not be dyed to correspond to the color of the warp and woof threads entering into the structure prior to weaving the same.

20 I claim:

1. A fabric having warp and woof threads and a dyeable reinforcing thread incorporated therein and retained by said warp and weft threads, said reinforcing thread being 25 of resilient cellulose material.

2. A ribbon comprising a body portion, and a plurality of relatively coarse and resilient threads of cellulose material incorporated into said body portion along opposite edges thereof.

3. A ribbon comprising a body portion, a plurality of relatively coarse and stiff threads of resilient cellulose material incorporated into said body portion along opposite edges thereof, a second group of relatively coarse and stiff threads of resilient cellulose material incorporated into said body portion in proximity to each of the first named groups of threads.

4. A ribbon comprising a body portion, 40 a relatively resilient thread of cellulose material incorporated into said body portion along the edge thereof, and a second relatively resilient reinforcing thread of cellulose material incorporated into said body portion adjacent the first-named thread and running in the same direction.

5. A ribbon comprising a body portion, a group of relatively resilient reinforcing threads of cellulose material incorporated 50 into said body portion along opposite edges thereof, a second group of relatively resilient reinforcing threads of cellulose material incorporated into said body portion adjacent each of the first-named groups of 55 threads and running in the same direction.

In testimony whereof, I have affixed my signature to this specification.

EMIL SCHLOSS.
